RING AND TRAVELER FOR SPINNING AND TWISTING FRAMES

Ralph Ragan, Atlanta, Ga., assignor to Steel Heddle Manufacturing Company, Philadelphia, Pa., a corporation of Pennsylvania

Application June 19, 1934, Serial No. 731,248

12 Claims. (Cl. 118—59.5)

My invention relates to rings and travelers for spinning and twisting frames.

The principal object of my invention is to provide a ring and traveler for spinning and twisting frames, having means for effectively lubricating the same so that the surface of the ring against which the traveler bears in its movement will at all times be properly lubricated, and wear on the ring and traveler thus reduced to a minimum.

A further object of my invention is to provide a lubricated ring and traveler which are so constructed and arranged that fouling of the yarn by the lubricating medium will also be reduced to a minimum.

A further object of my invention is to provide a lubricating ring and traveler which are so constructed and arranged that an ample supply of lubricating oil may be provided, thus avoiding the necessity of constant attention to insure proper lubrication.

A further object of my invention is to provide a ring and traveler construction in which the traveler is provided with means for insuring a large bearing surface at the place where the traveler contacts with the ring in its movement about the ring.

A further object of my invention is to provide an improved form of traveler which will have no tendency to cock and chatter during the operation.

A further object of my invention is to provide a ring and traveler construction by means of which a more uniform twist in the yarn will be obtained, and irregularities in and breakage of the yarn will be greatly reduced.

The nature and characteristic features of my invention will be more readily understood from the following description, taken in connection with the accompanying drawing forming part hereof, in which:

Figure 1 is a vertical central sectional view illustrating a ring and traveler embodying the main features of my present invention;

Fig. 2 is a top or plan view thereof, partly broken away; and

Fig. 3 is an elevational view of the traveler detached, looking from the inner side.

It will, of course, be understood that the description and drawing herein contained are merely illustrative, and that various modifications and changes may be made in the structure disclosed without departing from the spirit of my invention.

Referring to the drawing, 10 is the traveler ring, made of any preferred material, such for

example as any of the alloy steels commonly used for such purpose. This ring may be hardened and polished in the usual manner. The ring 10 has a base portion 11, of sufficient area in cross-section to afford the necessary rigidity.

A portion 12 extends upwardly from the base portion 11 of the ring 10, being so shaped as to provide an inner bearing surface 13, which is made frusto-conical for a purpose to be presently explained. The small diameter of the frusto-conical bearing surface is disposed upwardly. At the upper part of the upwardly extending portion 12 there is provided an inwardly extending flange 14 which serves to limit the upward displacement of the traveler to be hereinafter described. A small groove 15 is preferably provided where the upper edge of the bearing surface 13 joins the under surface of the inwardly extending flange 14.

An oil reservoir 16, preferably made of pressed sheet metal, is mounted on the ring 10 by means of an upwardly extending rim 17, which frictionally engages the outer surface of the base portion 11 of the ring. The oil reservoir 16 is so shaped as to provide an annular chamber 18, disposed below the base portion 11 of the ring. In this annular chamber 18 there is mounted an annular wick 19, made of felt or other suitable material, which extends upwardly from the bottom of said annular chamber, and terminates at its upper end in an annular lip portion 20, which engages the lower part of the inner frusto-conical bearing surface 13 of the ring 10.

The inner wall 21 of the oil reservoir 16 extends upwardly to form a guard, to shield the working surface of the ring 10 against the accumulation thereon of the fly and grit which are thrown centrifugally outwardly during the spinning and twisting operation. This guard wall 21 of the oil reservoir also serves to prevent broken ends of the yarn from coming in contact with the bearing surface of the ring and becoming fouled by the oil thereon. Furthermore, the wall 21 serves to prevent the base of the bobbin from contacting with the traveler, as sometimes happens with the ordinary rings and travelers.

The guard wall 21 is preferably provided, at one portion of its circumference, with a cut-out 22, to permit the traveler to be snapped in place on the ring 10 and to be removed therefrom.

The traveler comprises a length of wire or a metallic strip, suitably bent to provide a curved portion 23, around which the yarn passes in the usual manner. The traveler is also provided with a portion 24 extending outwardly over the top

of the ring 10, then downwardly on the outside of the ring, as at 25, to prevent the traveler from becoming detached from the ring after it is snapped in place thereon.

5 The traveler is also provided with a downwardly extending portion 26, which passes below the inwardly extending flange 14 of the ring 10, and thence extends outwardly, as at 27, where it is secured to a tail piece 28 which bears against 10 the frusto-conical bearing surface 13 of the ring.

15 The outer surface of the tail piece 28 is shaped complementally to the bearing surface 13 of the ring 10, thereby affording a bearing surface of considerable area, which serves to reduce the wear on the traveler as well as on the ring.

20 The tail piece 28 of the traveler is preferably of a peculiar conformation and arrangement. The lower outwardly extending portion 27 of the traveler is secured to the tail piece 28 near one 25 end thereof (see Fig. 3), so that the greater portion of the mass of the tail piece is disposed to one side of the place of engagement of the yarn with the traveler, for a purpose to be presently explained.

25 Preferably, also, the ends of the tail piece 28 of the traveler are inclined, as at 29 and 30, and the upper corner of the short end of said tail piece is slightly rounded, as at 31.

30 The operation of the ring and traveler, as above described, may now be explained. A suitable quantity of oil having been placed in the annular chamber 18 of the reservoir 16, the same will be fed upwardly by the wick 19 to the lower part of the frusto-conical bearing surface 13 of 35 the ring 10. The oil will then be evenly spread over said bearing surface of the ring, by reason of the agitation of the air caused by the movement of the traveler, and also by reason of the natural creeping characteristic of the oil. However, the top surface of the ring 10 will be maintained free of oil, and there will be no throw-out of the oil during the running.

40 In the manner above described, the frusto-conical bearing 13 of the ring 10 will be effectively lubricated, and a film of the oil will be maintained over the entire surface of said ring. It is to be noted that during the operation the traveler bears only on the lubricated surface of the ring.

45 50 The bearing surface 13 of the ring will be protected from the fly and grit by the vertically extending wall 21 of the oil reservoir 16. This wall 21 will also serve to prevent the loose end of the yarn, which flies outwardly whenever a breakage 55 occurs, from coming in contact with the oil on the bearing surface 13 of the ring 10, and becoming fouled thereby.

60 65 As hereinbefore pointed out, the tail piece 28 of the traveler affords a bearing surface of considerable area, and the inclined ends 29 and 30 of said tail piece will aid in distributing the oil more evenly between the bearing surfaces of the tail piece 28 and the ring 10, as well as serving to bring about a more effective agitation of the air adjacent the bearing surface 13 of the ring, for the purpose of assisting in the spreading of the oil thereover.

70 75 The purpose of the inclined frusto-conical surface 13 of the ring, and the coacting tail piece 28 of the traveler, may now be explained. The combined effect of the gravitational and centrifugal pull on the mass of the traveler and the tail piece is such as effectively to overcome the force imparted by the yarn, which force tends to raise the traveler and pull the same inwardly.

80 It will be seen that when the traveler rotates at high speed about the ring 10, the inclination of the bearing surface 13 of the ring will tend to cause the traveler to be impelled downwardly against the tension of the yarn, and thereby an effective balance will be obtained, so that in reality but little pressure will be exerted by the traveler against the ring.

85 Furthermore, the provision of the unsymmetrically disposed tail piece 28 of the traveler, 10 by reason of the centrifugal force exerted thereon, will maintain the traveler in a radial position notwithstanding the tendency of the yarn to cock the same by reason of the angularity at which the yarn runs off from the traveler to the 15 cop or bobbin. In this manner, the tendency of the traveler to chatter will be eliminated.

90 It will thus be seen that there is provided a novel form of ring and traveler therefor, which are so constructed and arranged as to insure a 20 proper lubrication of the bearing surfaces, and by means of which fouling of the yarn by the oil will be substantially eliminated, wear will be reduced to a minimum, a more uniform twist will be imparted to the yarn, and breakage of 25 the yarn will be greatly reduced.

I claim:

1. A spinning ring having an inner bearing surface; and a free running traveler cooperating therewith having a yarn engaging part and a tail 30 piece having an enlarged bearing surface complementary to and entirely within the confines of the bearing surface of the ring, said tail piece having the greater portion of its length disposed to one side of the yarn engaging part. 35

2. A spinning ring having an inner frusto-conical bearing surface; and a traveler cooperating therewith having a yarn engaging part and a tail piece having an enlarged bearing surface complementary to and entirely within the confines of the 40 frusto-conical bearing surface of the ring, said tail piece having the greater portion of its length disposed to one side of the yarn engaging part.

3. A spinning ring having an inner bearing surface; and a free running traveler cooperating 45 therewith having a yarn engaging part and a tail piece having an enlarged bearing surface complementary to and entirely within the confines of the bearing surface of the ring, said tail piece having its ends inclined.

4. The combination with a spinning ring having a bearing surface, and a traveler cooperating therewith, of an oil reservoir having an annular chamber disposed below the bearing surface of the ring; and an annular wick mounted in said chamber below said bearing surface and having its upper end in contact with the lower portion of the bearing surface of the ring. 55

5. The combination with a spinning ring having a bearing surface, and a traveler cooperating therewith, of an oil reservoir having an annular chamber disposed below the bearing surface of the ring; and an annular wick mounted in said chamber and having its upper end provided with a lip portion in contact with the lower portion of the ring. 65

6. The combination with a spinning ring having a bearing surface, and a traveler cooperating therewith, of an oil reservoir having an annular chamber disposed below the bearing surface of the ring; and an annular wick mounted in said chamber and having its upper end provided with a lip portion in contact with the lower portion of the ring; said reservoir also having an inner wall ex- 75

tending upwardly to serve as a shield for the bearing surface of the ring.

7. A spinning ring having an inner frusto-conical bearing surface; a traveler cooperating therewith having a yarn engaging part and a tail piece having a surface complementary to the bearing surface of the ring, said tail piece having the greater portion of its length disposed to one side of the yarn engaging part; an oil reservoir having an annular chamber disposed below the bearing surface of the ring, and also having an inner wall extending upwardly to serve as a shield for the bearing surface of the ring.

8. A spinning ring having an inner frusto-conical bearing surface; a traveler cooperating therewith having a yarn engaging part and a tail piece having a surface complementary to the bearing surface of the ring, said tail piece having the greater portion of its length disposed to one side of the yarn engaging part; an oil reservoir having an annular chamber disposed below the bearing surface of the ring; and an annular wick mounted therein having its upper end in contact with the lower portion of the bearing surface of the ring.

9. A spinning ring having an inner frusto-conical bearing surface; a traveler cooperating therewith having a yarn engaging part and a tail piece having a surface complementary to the bearing surface of the ring, said tail piece having the greater portion of its length disposed to one side of the yarn engaging part; an oil reservoir having an annular chamber disposed below the bearing surface of the ring; an annular wick mounted

therein having its upper end in contact with the lower portion of the bearing surface of the ring; and said reservoir also having an inner wall extending upwardly to serve as a shield for the bearing surface of the ring.

10. A spinning ring having an inner frusto-conical bearing surface, and a traveler cooperating therewith having a yarn engaging portion and a bearing portion comprising a block provided with an enlarged bearing surface complementary to and engaging the bearing surface of the ring, the yarn engaging portion comprising a member extending over the top of the ring, and one of the ends of the yarn engaging portion being fixedly secured to the bearing portion.

11. A spinning ring having an inner frusto-conical bearing surface adapted to be engaged by a portion of a traveler, said ring also having a flange extending substantially horizontally inward from edge portions of said bearing surface to limit upward displacement of a traveler mounted on the ring.

12. A spinning ring having an inner frusto-conical bearing surface; and a traveler cooperating therewith having a yarn engaging part and a part having an enlarged bearing surface complementary to and engaging the bearing surface of the ring, said bearing surface of the traveler being less in vertical extent than the vertical extent of the bearing surface of the ring, said ring having an upper flange extending substantially horizontally inward to limit upward displacement of the traveler.

RALPH RAGAN.
